UNITED STATES PATENT OFFICE

HERBERT C. BUNTING, OF SEATTLE, WASHINGTON, ASSIGNOR TO NATIONAL VENDING SERVICE, INC., OF CHICAGO, ILLINOIS, A CORPORATION OF ILLINOIS

SINGLE PACKAGE VENDING MACHINE

Application filed December 10, 1921, Serial No. 521,328. Renewed August 4, 1930.

My invention relates to vending machines and particularly to such as are adapted to hold and deliver a single package, also to such as retain the coin in full view until the machine is reset, and only then to release the coin.

The primary object of my invention is to provide a vending machine which will accomplish these purposes, namely, to deliver its 10 single package and to retain the coin in its operating mechanism and only to release the coin when the machine has been reset or reloaded.

Associated with the general object above, 15 it is my object to produce a compact and neat vending machine.

A further object is to provide means in a vending machine which will lock either the coin-controller mechanism or the package 20 handling mechanism, or both, in actuated position, that is, in the position the parts assume after a package has been delivered.

A further object is to provide a vending machine in which the parts are so locked in 25 actuated position and which requires special manipulation, or in some cases a special key or releasing tool, to reset parts in the normal position.

Other objects will be ascertained from a 30 study of the following specification and claims and the drawings which form a part hereof.

My invention comprises those novel parts and combinations thereof which are shown in 35 the accompanying drawings, described in the specification, and particularly pointed out in the claims terminating the same.

In the accompanying drawings I have 40 shown my invention in the form which is now preferred by me.

Figure 1 is an elevation of my vending machine, parts being shown in normal or set position.

Figure 2 is an elevation of the machine 45 with the cover removed, parts being shown in normal position and the machine being loaded.

Figure 3 is a view similar to Figure 2, of 50 the coin-controlled portion of the machine, parts being shown in the actuated position,

or that position they would assume after a package has been ejected.

Figure 4 is a section on line 4—4 of Figure 55 3, parts being shown at the instant of release to eject a package.

Figure 5 is a section on line 5—5 of Figure 3, parts being shown in the normal or set position.

Figure 6 is a section on line 6—6 of Figure 60 3, parts being shown in the position they would assume as they move toward the ejecting position.

Figure 7 is a section on line 7—7 of Figure 3, parts being shown in normal position.

Figure 8 is a section on line 8—8 of Figure 65 3.

Figure 9 is an edge view of the package carrier.

My vending machine is particularly adapted for use in public places where it must necessarily be small and inconspicuous, by reason of lack of space, of harmony with its surroundings, or for other reasons. I have therefore shown my device as vending only a single package, as of chewing gum. 70

Within a casing 9 is slidably mounted a carrier 8 provided with fingers 81 at its outer end, which are adapted to engage the outer end of the package P to retain it within the machine. The carrier 8 may also support an 80 ejector plate 82 at its inner end, backed by a spring 83, for limited movement relative to the carrier, but this must not be confused with the primary ejector which will be later described. The plate 82 and spring 83 are 85 merely supplemental ejectors to give a final push to the package itself.

The carrier 8 is guided in confined guides 94 of less width than the casing 9, the distance between them being slightly greater 90 than the width of the package P. At their ends the guides 94 are cut away, and opposite sides of the delivery opening 91 from the casing 9 are provided with inturned hooks 95 which are adapted to receive the hooked 95 ends 81 of the carrier. The ends of the carrier are arranged to spring outward when they are released from the confining guides 94, as is shown by dot-and-dash lines in Figure 2. The carrier has a certain amount of 100

spring, as is shown by comparing its stressed and unstressed forms, in Figures 2 and 9, respectively. A catch 85 of spring material is secured to move with the carrier 8 and may be provided with a lateral offset 86 for a purpose to be later described. This catch 85 engages with a fixed catch 98 upon the casing 9 and retains the carrier 8 therein until the catch 85 is released. The casing 9 is preferably provided with suitable windows 96 and 97 adjacent the positions assumed by the package and by the coin, respectively.

A coin slide 10, guided suitably, as in carrier 93 removably secured in the casing 9, is provided with a suitable opening 11 for the reception of a coin, the casing 9 having an opening 90 registerable with the opening 11 when parts are in their normal position. The slide 10 may also be provided with a suitable handle 12. The coin slide is shown as guided in the coin slide carrier 93 by means of a rib 93' slidable in a slot 92. A double ratchet bar 1 is suitably secured to the coin slide 10 to move therewith, as by means of pins or rivets 13 passing through the slide 10, rib 93' and bar 1, and these members are to all intents and purposes integral one with the other, though the ratchet bar 1 is spaced from the coin slide 10 by a partition of the carrier 93. A spring 14 anchored at one end to the casing and secured at its other end to the coin slide or to a pin 13 which is projected therefrom outside of the carrier 93, serves to retain the coin slide in its normal position as shown in Figure 5.

On one side of the ratchet bar 1 are teeth 15 which are adapted to be engaged by a dog 2 which is pivoted at 20 in the casing 9 and which is held in the path of the teeth 15 by means of a spring 21. This dog 2 is adapted to lock the coin slide or the ratchet bar 1 against movement in the actuating direction. The dog 2 carries a pin 22 which projects into the path of movement of the coin C and which may be moved by a coin of the proper denomination prior to engagement of the dog 2 with the teeth 15 to remove the dog from the path of these teeth, and thus to permit movement of the coin slide and ratchet bar in the actuating or ejecting direction.

A carrier release 16 is supported at the inner end of the bar 1, being that end which is adjacent the carrier 8. Preferably it projects laterally and is intended to engage the laterally projecting member 86 which forms a part of the catch 85. These two members have their supports out of alinement with any portion of the other member so that they may not be engaged to block the operation of the mechanism at any time. The carrier release 16 is positioned to operate only after the teeth 15 have passed the dog 2, and upon suitable engagement of the members 16 and 86 the catch 85 is released from the fixed stop 98 and ejection of the carrier 8 with its pack-

age P is permitted. The forward edge 18 of the support for release 16, or any other member movable with the coin slide 10 and ratchet bar 1, contacts with a boss 88, or other portion of the package carrier 8, to give it a slight initial push and to start it in the ejecting direction.

Means may be provided for locking the package carrier 8 in ejected position, to be releasable only as a new package is placed in position within the machine. A spring catch 7 is secured to the casing 9 in position to engage the carrier 8 in its ejected position; preferably at its inner or upper end. A bend 71 forming part of the catch 7, lies in the path of the plate 82. Ordinarily, when the machine is loaded, the catch 7 lies alongside of the carrier 8, but engages the carrier when this moves outwardly. As a fresh package is pushed into the machine, it engages and moves inwardly the plate 82, the latter in turn engaging the bend 71 to force the catch 7 out of engagement with the carrier 8, whereupon the carrier moves inwardly to its normal or loaded position, where it is held by the catch 85.

Means are provided for locking the coin slide in the position it assumes upon ejection of the package P, with the coin in full view through the window 97. I have shown the ratchet bar 1 as provided with teeth 17 which face oppositely to the teeth 15 and which may be upon the opposite side of the bar 1. A second dog 4 is pivoted at 40 in the casing 9 and is normally held in engagement with the teeth 17 by means of a spring 41. A pin 42 stands above the surface of the dog 4 to be engaged by a releasing trip.

The releasing trip 5 is carried upon a lever 50 pivoted at 51 upon the resetting slide 3, in position to engage the pin 42 as it passes, the slide being guided upon pins 30 supported from the casing 93 and passing through slots 32 of the slide. The trip 5 is shown as upon the opposite side of the resetter 3 from the lever 50, the pin 52 connecting it to the lever 50 passing through a slot 32 and having lateral movement only therein. The trip 5 is inclined upon both faces relative to its direction of movement, and as it passes outwardly of the pin 42 moving towards the package carrier 8, into its normal position, the lever 50 is moved to one side and the position of the pin 42 and dog 4 is not disturbed. Upon being moved in the opposite direction, however, by engagement of a special reloading tool T, shown by broken lines in Figure 2, with an upturned toe 33 of the resetting slide 3, the opposite face of the trip 5 engages the pin 42, and the pin 52 being held against inward movement by the edge of the slot 32, the pin 42 and the dog 4 are forced outwardly, in this manner to release the dog from the teeth 17. As this occurs the action of the spring 14, which has been extended,

5 returns the bar 1 and the coin slide 10 to their normal position. It will be seen that the spring 31 is extended between a fixed post 30 and a post 53 carried upon the lever 50, and thus serves both to maintain the lever 50 and trip 5 in proper position, and to maintain the slide 3 in operative position, except when engaged by the reloading tool 7.

10 The mechanism cannot be operated without the use of a proper coin, for if an attempt is made to push the coin slide 10 in the actuating direction without having previously inserted any coin, or having inserted a coin of improper size in the recess 11, the dog 2 will 15 not be disengaged from the teeth 15 and further movement of the coin slide is prevented. Reliance is placed on the fact that the coin is visible through the window 97 to prevent the use of slugs. However, if a 20 proper coin is inserted in the recess 11, this will contact with the pin 22 to move the dog 2 out of the path of the teeth 15. Immediately thereafter the dog 4 is engaged with its teeth 17 to prevent return of the coin 25 slide to normal position. However, as the slide 10 is pushed farther in the actuating direction, its handle 12 may enter a recess 99 in the casing which is adapted to receive it, and eventually the release 16 engages the 30 member 86 to release the catches 85 and 98. At this instant, as shown in Figure 4, the ejector edge 18 of the ratchet bar contacts with the boss 88 of the package carrier, initiating the ejection of the carrier 8 with its 35 package P.

Once free of the confining guides 94, the 40 ends 81 of the carrier spring outwardly and force the entire carrier to move towards the delivery opening 91. The ends 81 are finally received within the hooks 95. The action 45 of the supplemental ejector plate 82 then assists in the further projection of the package P beyond the limit of the delivery opening 91 to a point where it can be grasped, although the inwardly bowed sides of the carrier 50 keep it from falling out. By this time the coin slide has advanced the coin until it is opposite the circular window 97 where it may be plainly seen, and as the machine 55 will be used in public places, this window will show what has been inserted and this fact will act as a great deterrent to the use of slugs. Engagement of the dog 4 with the teeth 17 has locked the slide against return movement.

To remove the coin it is necessary to withdraw the slide 10, and this can best be accomplished with the use of the key or reloading tool T, although the device may be so arranged that the mere insertion of the package 60 will release the coin slide. This reloading tool may be made in various shapes, and the faces of the ejector plate 82 and the inner end of the carrier 8 may be formed with suitable recesses or openings 88 to receive the key.

This is inserted from the delivery opening and is passed through the holes in the plate 82 and the end of the carrier 8, which are best shown in Figure 8 as notches 89, until it can engage with the foot 33 of the resetter. Together with the insertion of the key a new package P would ordinarily be pushed into position in the carrier 8 and this would be pushed into the casing 9 with the key until the catches 85 and 98 were again in engagement. At the same time the resetting slide 3 would be pushed back in the same direction, and as the trip 5 passes the pin 42 the dog 4 is released and, as described above, the action of the spring 14 returns the rack bar 1 and the coin slide 10 to its normal position. The coin can then be removed through the opening by which it was inserted, and the machine is loaded and ready for another sale.

85 In case of any defect in the coin-controlled mechanism, or if it is ever desired to remove the same for any reason, the carrier or inner casing 93 may be removed bodily from the outer casing, and as all of the coin-controlled mechanism is secured thereto, it may all be removed at once, and as a unit.

What I claim as my invention is:

1. In a coin controlled vending device, in combination a coin slide, means releasable by a coin for locking said slide against movement in the actuating direction and separate means independent of any coin and the material to be vended for locking the slide in actuated position after each actuating movement thereof.

95 2. In a coin controlled vending device in combination a coin slide, a coin releasable dog engageable therewith to lock the slide against movement in the actuating direction and a second dog brought into action by the movement of the slide for locking the slide against a return movement from the actuated position, said second dog acting independent of any coin and independent of the material to be vended.

105 3. In a coin controlled vending device in combination a coin slide, a dog normally engageable therewith to prevent the movement thereof in the actuated direction, a coin engaging part carried by said dog and projecting into the path of the coin to permit disengagement of the dog and slide upon engagement of said coin engaging part by a proper coin and a second dog engageable with the coin 110 slide as the latter moves in the actuating direction to prevent a return movement after each actuating movement thereof, said second dog acting independent of any coin and independent of the material to be vended.

115 4. In a coin controlled vending device in combination a coin slide, a dog normally engageable therewith to prevent movement thereof in the actuating direction, a coin engaging part carried by said dog and pro-

- jecting into the path of the coin to permit disengagement of the dog and slide upon engagement of said coin engaging part by a coin and a second dog engageable with the coin slide as the latter moves in the actuating direction to prevent a return movement after each actuating movement thereof, said second dog acting independent of the material to be vended and key controlled means for releasing said second dog to permit return of the coin slide to normal position.
5. In a vending machine a coin mechanism having a coin engaging actuating member movable longitudinally with relation to said machine from normal position to permit ejection of a package, means actuated by the coin for releasing said member, teeth intermediate the ends of said actuating member, a dog actuated by the coin mechanism which permits the forward movement thereof but arranged for engaging said teeth and locking said member against return to normal position and a key controlled trip operable to release said dog.
10. In a vending machine, in combination, a coin slide, means releasable by a coin for locking said slide against movement in the actuating direction, a dog for locking the slide against return movement from the actuating direction, a resetting slide adapted to be engaged by a key to move it from normal position, and a trip carried by said resetting slide and operable upon movement thereof from normal position to release said dog, and inactive upon its return to normal.
15. In a vending machine, in combination, a coin slide movable from normal position to permit ejection of a package, means releasable by a coin for locking said slide against movement from normal position, a dog for locking the slide against return to normal position, a pin projecting from said dog, a spring-held resetting slide slidable past said pin, and a double-faced trip carried by the resetter and adapted to release said dog upon movement of the resetter in one direction, and to be itself displaced by the pin upon its return movement.
20. A vending machine comprising an article holder, a coin slide in alignment therewith, two locking devices for the coin slide for locking it against movement in its actuating direction and in its retracting direction, the first mentioned locking device being released by the coin, the other locking device holding the coin slide and the article holder in their discharge positions and releasing means independent of any coin for releasing said latter locking device.
25. In a vending machine, a casing, a coin opening therein, a movable package carrier in said casing, a coin controlled delivery mechanism for moving said package carrier and comprising a coin moving part having a coin receiving portion for receiving the coin in-
- serted through said opening, means actuated by the coin for releasing said coin moving part, means independent of the material to be vended for locking said coin moving part in delivery position after each delivery of the material to be vended, locking means for said package carrier and means for returning said coin moving part so that the coin in the coin receiving part thereof will be opposite the coin opening in the casing so that it can be removed therethrough.
30. A vending machine comprising a casing, having a coin opening therein, a coin moving part having a coin receiving portion opposite said opening when the parts are in their initial position, means actuated by the coin for releasing said coin moving part, a discharge opening in said casing, a package carrier adapted to be inserted in said discharge opening, to its operative position in said casing, and a releasing device actuated by said coin moving part when a coin is inserted in the coin receiving portion thereof for releasing said package carrier so that it may be moved to its discharge position so that the package may be removed from the casing.
35. Signed at Seattle, King County, Washington, this 3rd day of December, 1921.
- HERBERT C. BUNTING.
